UNITED STATES PATENT OFFICE.

JOHN S. FORBES, OF OVERBROOK, PENNSYLVANIA.

HEATER.

Application filed May 3, 1923. Serial No. 636,402.

To all whom it may concern:

Be it known that I, JOHN S. FORBES, a citizen of the United States, residing in Overbrook, Pennsylvania, have invented a 5 Heater, of which the following is a specification.

One object of this invention is to provide a convenient, economical and compact form of heater particularly adapted for heating 10 small rooms. A further object of my invention is to provide a convenient and efficient device for heating or drying objects requiring a relatively mild degree of heat, and said invention especially contemplates the 15 provision of a convenient and inexpensive form of heating shelf, together with novel means for supporting this in either of two adjusted positions.

Another object of the invention is to provide 20 a heating plate with novel means for maintaining it at any of several different temperatures, the invention including also novel means for connecting the several parts of the device so that these may be easily and 25 quickly assembled and inspected.

These objects and other advantageous ends I attain as hereinafter set forth, reference being had to the accompanying drawings, in which,

30 Figs. 1 and 2 are perspective views illustrating my heater with its adjustable element in its lowered and raised positions, respectively;

Fig. 3 is a perspective view of the main 35 supporting frame for my heater;

Figs. 4 and 5 are perspective views respectively of the front and rear of the back plate which forms a part of my apparatus;

Fig. 6 is a vertical section on the line 40 6—6, Fig. 1;

Figs. 7 and 8 are perspective views of the front and back faces of the plate which carries the heating elements and the structures associated therewith;

45 Fig. 9 is a perspective view of the face plate of my heater;

Figs. 10 and 11 are perspective views of certain of the protecting sheets preferably used in connection with my heater;

50 Fig. 12 is a diagram illustrating the electrical connections of the heating elements and controlling switch forming part of my heater;

Fig. 13 is a front elevation, partly in verti-

cal section, illustrating the detail construction of one of the electrical heating elements;

Fig. 14 is a detached perspective view further illustrating the preferred construction of the heating element;

Fig. 15 is a perspective view of one of the 60 connectors for the heating coils;

Fig. 16 is a perspective view illustrating my heater as adapted to use gas instead of electricity;

Fig. 17 is a vertical section on the line 65 17—17, Fig. 16;

Fig. 18 is a perspective view of the supporting frame for that form of my heater shown in Fig. 16;

Figs. 19 and 20 are perspective views illustrating the front and rear faces of the back plate for the gas heated form of my invention;

Figs. 21 and 22 are perspective views of the front and rear faces of the plate carrying the gas burner and its associated parts; and,

Fig. 23 is a perspective view of a baffle plate forming part of the structure shown 80 in Fig. 17.

In the above drawings and referring to Figs. 3 and 6, 1—1 are two parallel and vertically mounted lengths of angle iron joined at their upper ends by a cross bar 2 having projecting extremities forwardly offset from the plane of the back of the angle irons 1—1. The lower ends of the latter are cut away for a suitable distance and the extremities of their bodies are turned up to form hooks 3—3. Carried by and fixed to the angle irons 1—1 of the frame is a block 4 of insulating material carrying a pair of contact clips 5—5 having terminals 6 and 7 for connection to a pair of conductors leading from any suitable source of electric current.

The frame formed by the elements 1—1—2 is designed to support a back plate 8, (Figs. 4 and 5) preferably made of sheet or cast metal having an edge flange and of a generally rectangular shape. This back plate has on the upper part of its rear face a pair of lugs 9—9 designed to fit back of the offset ends of the cross bar 2, so as to hold said plate to its supporting frame, which is thus completely enclosed thereby. The lower part of the back plate 8 has fixed to it in any suitable manner a cross bar 10 having offset ends designed to fit into the hooks 3 so that

said plate and the structures carried by it may be removably mounted on the frame 1—1—2 by the simple operation of engaging the lugs 9—9 and ends of the cross bar 10 with the cross bar 2 and hooks 3.

Adjacent the center of the back plate 8 is an opening 11, whose lower part is designed to receive the forwardly projecting insulating block 4 with its fuse terminals 5 and 6. In addition I provide a second insulating block 12 mounted on the back plate 8 so as to project through the upper part of the opening 11. This second block 12 carries a pair of contact clips 13—13, respectively aligned with the clips 5—5 and immediately adjacent the same in such positions that suitable cartridge fuses may be mounted in and caused to electrically connect each of the clips 5 with one of the clips 13.

20 The back plate 8 has projecting upwardly from its top edge an extension 14 on which is mounted a suitable multi-point switch 15, and as shown in Fig. 12, one contact 16 of this switch is connected through a conductor 17 with one of the fuse terminals 13. The other three terminals 18, 19 and 20 of said switch are connected to three heating coils 21, 22 and 23 in the manner indicated in Fig. 12 and as hereinafter explained.

30 From the upper part of the front face of the back plate 8 projects a pair of bearing lugs 24—24 having recesses for the reception of pivots or trunnions 25—25 forming part of or suitably fixed to the rear face of a rectangular flanged plate 26 having substantially the same general outline as the back plate 8, to which it is movably connected by said trunnions. On the front or outer face of this plate 26, I mount two parallel outwardly projecting members 27—27 of channel section serving to support three heating elements 21^a, 22^a and 23^a, respectively including the coils 21, 22 and 23.

40 As shown in Figs. 13 and 14, each of the heating elements includes a core 28 of refractory material such as porcelain, lava or the like, on which the wire 21 to be heated, is wound preferably in a helical groove. At each end the core 28 has mounted upon it a refractory bushing 29 and the two bushings of each core carry coaxially therewith a suitably perforated cylindrical protective casing 30 usually of sheet metal. As shown in Fig. 14, each of the ends of the core 28 is formed with a longitudinally extending slot 31 designed for the reception of the inwardly turned end 32 of a split sheet metal sleeve 33 whose opposite end 34 is rolled up to form a tubular channel for the reception 50 of the end of the winding 21. When said sleeve 33 is applied to the end of the core 28 with its inwardly turned end 32 in the slot 31 thereof, the end of the winding on said core will be extended through the rolled up end 34 and thus electrically connected to

the sleeve, which constitutes a terminal for said winding projecting outside of the refractory bushing 29.

For the purposes of my invention, an end of the winding 23 of one heating element is 70 electrically connected to the adjacent end of the winding 22 and the second end of the latter winding is likewise electrically connected to one end of the winding 21. For this purpose, I provide metallic strips 35 75 (Fig. 15) having their ends formed to receive and be clamped upon the sleeves 33. As shown in Fig. 12, the strip 35 connecting the windings 22 and 23 is connected to the terminal 19 of the switch 15 and the strip 80 connecting the windings 21 and 22 is similarly connected to the terminal 20 of said switch. The free end of the winding 21 is connected to one of the fuse clips and the free end of the winding 23 is connected to 85 the switch terminal 18.

For the purpose of connecting the heating elements on the plate 26 with the switch on the fixed plate 8 so as to permit relative movement of the former, I lead the conductors from said elements through a pair of oppositely disposed holding blocks 36 on the upper part of the rear face of the plate 26, extending said conductors from said blocks in two parallel pairs toward and into a receiving block 37 at the middle of the front face of the back plate 8 which is provided with passages from which said conductors run to the fuse clips 13 and to the switch 15. Between these blocks 36—37—36, the conductors run immediately adjacent to and parallel with the pivotal axis of the trunnions 25, so that the plate 26 may be swung through an angle of substantially 90° from a vertical to a substantially horizontal position without injury to said conductors or interference with the supply of current to the heating elements.

As shown in Fig. 7, the front face of the plate 26 which carries the heating elements, has four hook-like lugs 40 preferably placed adjacent its corners. These are designed to receive suitable projecting lugs 41 on the flanged cover plate 42 so as to removably support the same in such position as to enclose the heating elements and their supporting structure. This plate 42 is preferably made of highly polished or enameled sheet or cast metal, and as shown in Figs. 1 and 9, is formed with a series of openings 43 in its top side. This cover 42, with the heating elements and their supporting plate 26, are free to be swung on the bearings 24—24 from the substantially vertical position as shown in Fig. 1, to the position 110 shown in Fig. 2, in which the extended flat outer face of said cover is horizontal, and for the purpose of maintaining said parts in this latter position, I provide two pairs 115 of joined bars or links 44—45, of which the 120

links 44 are respectively pivoted or hinged to lugs 46 on the rear face of the plate 26, while the links 45 are respectively pivoted or hinged to lugs 47 on the lower part of the back plate 8. The bars 44 are each provided with a suitable projecting stop or lug 48 (Figs. 2 and 6) in order to maintain them in the extended positions necessary to hold the cover 42 in its horizontal position. At the same time they permit said links or bars to buckle and swing from their extended positions to parallel positions when said cover with the heating coils is to be moved to the vertical position.

In order to prevent excessive heating of the flat face of the cover 42, by the heating elements, I may under certain conditions provide a perforated shield 50 (Figs. 6 and 11) formed to be carried by the members 27 between said heating elements and the rear face of the cover, I may likewise mount between the back plate 8 and the adjacent face of the plate 26 a suitably formed metallic or other enclosing and protective sheet 25 or guard 51 (Fig. 10).

With the above described arrangement of parts it is obvious that the windings 21, 22 and 23 may be so supplied with current as to give three degrees of heat, the switch 15 being provided with a movable contact or contacts (not shown) for accomplishing this end. With the parts in the positions illustrated in full lines in Fig. 6, air is free to enter my heater at the bottom thereof and to flow upwardly between the cover 42 and the plate 26 around the heating elements. Thereby its temperature is raised to the desired point and it may flow out through the openings 43 of the cover. When used in this manner, the device acts chiefly as an air heater although heat is also radiated from the front and side faces of the cover 42. When the latter is swung upwardly in the position in dotted lines in Fig. 6, its extended flat face is available for drying and heating small articles as well as for heating hot applications, containers or other objects.

Without departing from my invention, I may utilize gaseous or liquid fuel as the heating agent for my invention which for this purpose is constructed as shown in Figs. 16 to 23, inclusive. As before, I provide a supporting frame (Fig. 18) preferably including a cross bar 2^a and at least one vertically extending bar 1^a having a hook 3^a at its lower end. This frame is designed for attachment to a wall or other vertical supporting structure and has detachably mounted upon it a flanged back plate 8^a having lugs 9 at its upper portion for engagement with the offset ends of a cross bar 2^a and having a cleat 52 at the middle of its lower portion which engages with the hook 3^a.

Upon the back plate, as before, I mount a heating-element-carrying plate 26^a including trunnions 25^a formed to rotatably engage bearing lugs 24 on said back plate. On the front of the plate 26^a is mounted any suitable form of burner 53 for liquid or gaseous fuel and this is connected to a mixing chamber 54 on the rear face of said plate, adjacent which is mounted a fuel supply pipe 55 extending from a suitable source across the front face of the back plate 8^a. This supply pipe terminates in a valve 56 whose casing is connected to deliver axially into the mixing chamber 54 in the line of the trunnions 25^a, and one of said trunnions is formed to constitute the controlling stem for said valve, for which purpose it extends laterally through a suitable opening in the cover 42 outside of which it is equipped with an operating handle 57. As before, the cover 42 is hung to the plate on which the heating means is mounted, and it may be adjusted from its vertical to its horizontal position with the heating elements as previously described, being maintained in said latter position by a pair of coating links 44 and 45, connected between it and suitable lugs on the back plate 8^a. Inasmuch as the valve 56 and supply conduit 55 remain stationary, while the mixing chamber 54 swings with the cover 42 and plate 26^a, there is no interference with the supply of fuel and operation of the device, when the cover is adjusted from one to the other of its positions.

In order to prevent undue heating of the back plate and its associated parts, I preferably mount on the back of the plate 26^a a shield 51^a, for which purpose said plate is supplied with suitable rearwardly projecting studs 60 on which the shield is carried.

From the above description, it will be appreciated that the various parts of my device may be easily and quickly assembled or separated as may be desired, their construction being simple, rugged and of such a general nature as to remain in serviceable condition without attention for long periods of time. Obviously, the temperature to which the cover 42 may be heated, or the temperature of the air delivered from the device, may be widely varied without departing from my invention by alterations in the design and proportions of the heating elements, in order to suit my heater for various kinds of service.

I claim:

1. The combination in a heater of a supporting structure; a heat radiating plate hinged to and normally suspended from said structure and movable from a normal substantially vertical plane to a substantially horizontal plane; with means for maintaining said plate in the latter plane.

2. The combination in a heater of a supporting structure; a plate hinged to and normally suspended from said structure and movable from a normal substantially vertical to a substantially horizontal position; and heating means attached to and movable with said plate. 6. The combination in a heater of a back plate adapted for wall mounting; a cover plate mounted thereon; heating means mounted on and enclosed by the cover plate; and means for movably connecting said plates. 35
3. The combination in a heater of a supporting structure; a heating plate hinged thereto and free to be moved from a normal suspended substantially vertical to a horizontal position; heating means movable with said plate; and means for maintaining the plate in a substantially horizontal position. 7. The combination in a heater of a supporting structure; a substantially flat faced plate having a flange and connected to said structure with its flat face in a substantially vertical plane, there being openings through said plate for the passage of air; and heating means for said plate enclosed between it and the supporting structure. 40
4. The combination in a heater of a supporting structure; a flanged plate hinged to and normally suspended from said structure and formed with openings for the passage of heated air, said plate having a flat relatively smooth face; heating means for the plate; and means for supporting the plate with its face substantially horizontal. 8. The combination in a heater of a supporting frame adapted for mounting upon a vertical foundation; a back plate detachably mounted on said frame; a cover plate hinged to said back plate; heating means for the cover plate; and means for supporting said cover plate in a substantially horizontal plane. 50
5. The combination of a supporting structure; a plate connected to said structure and adjustable from a vertical to a horizontal position; heating means carried by and movable with the plate; and conductors for the supply of heating medium mounted on the supporting structure and connected to the heating means on the plate; said conductors including portions extending in the line of the hinge between the plate and supporting structure. 9. The combination in a heater of a supporting frame; a back plate mounted on said frame; a cover plate connected to said back plate movable into and out of a substantially horizontal position; electrical heating means carried by said cover plate; and an electric switch on the back plate for controlling the flow of current to said heating means. 55 60

JOHN S. FORBES.
